George Stroedinger Newark N. J.

Letters Patent No. X 6083

The libellule referred to in these Letters Patent and working part of the same, containing a description in the words of the said George Stroedinger himself of his improvement in the steel rolling mill, for midling and edging spring steel for carriage springs.

To all to whom these presents shall come. Be it known that I, George Stroedinger of Newark in the County of Essex and State of New Jersey, have invented a new and useful improvement in the steel rolling mill for midling and edging spring steel for carriage springs, and that the following is a full and exact description of the construction and operation of the said machine, as invented or improved by me.

No. 1. is a top horizontal roller with rounded projections to middle out the steel, and said, said said roller to raise and lower with four screws through the caps, with one cog wheel on the end of it.

No. 2. is a bottom horizontal roller with square grooves in, on the square end of this roller are two cog wheels; said rollers are to hold steel from one end up to the end with the cog wheels on the square end of the roller, are frames in which the movable perpendicular edging rollers are fastened; they move sideways so as to come opposite the grooves in the horizontal rollers No. 1 & 2, and raised & lowered so that the grooves in the edging rollers come opposite those in the horizontal rollers by passing through the cog; said frames are made in two pieces with sliding bray bars, with rooms in the center of the frames, the frames belong two other bars

To under or over the edge of the steel in the following manner: No. 147, which is a pair of circular sawing rollers with two cog wheels on to a roller which is provided with two tightening nuts, in each of these rollers one side is provided to edge the steel from the top to the bottom edge. No. 157 gives the same as No. 147, No. 15 is a horizontal shaft with cog wheel on the outside of the frame and inside the inside of the frame is another cog wheel with two tightening nuts, which drives the longitudinal rollers. No. 11 is the same as No. 10, No. 13 & 15 are required for the plates to pass through.

All of said machine is made of cast iron with boxes which are of traps.

The manner of using the foregoing improved machine is by placing the steel in the edge rollers and then passing it through the middle rollers and then through another pair of edge rollers.

The rollers are all driven by cog wheels, and when the plates come out after passing through they are in a finished state, both edge and middle out.

Accompanying this specification is a drawing of which you have the model on a scale of one quarter to the inches.

At Newark, N. J., July 10, 1830.

Witnessed
